(57) **CLAIM**

The ornamental design for a refreezable beverage cooler, as shown and described.

DESCRIPTION

This application claims priority from U.S. patent application Ser. No. 10/128,022, filed Apr. 23, 2002, entitled “Method and System for Use with a Consumable Beverage” invented by Hank Roth and Donna Roth.

FIG. 1 is a top perspective view of a refreezable beverage cooler according to our new design;

FIG. 2 is a bottom perspective view of the refreezable beverage cooler of FIG. 1;

FIG. 3 is a front elevational view of the refreezable beverage cooler of FIG. 1, the rear elevational view being a mirror image thereof;

FIG. 4 is a right side elevational view of the refreezable beverage cooler of FIG. 1;

FIG. 5 is a left side elevational view of the refreezable beverage cooler of FIG. 1;

FIG. 6 is a top plan view of the refreezable beverage cooler of FIG. 1; and,

FIG. 7 is a bottom plan view of the refreezable beverage cooler of FIG. 1.

The broken lines in FIGS. 1–7 represent environment and are for illustrative purposes only and do not constitute part of the claimed design; for example, any holes bounded by broken lines constitute environment and are not part of the claimed design.
